UNITED STATES PATENT OFFICE.

WILLIAM KOLB, OF ST. LOUIS, MISSOURI.

IRONING TABLE.

Application filed November 28, 1921. Serial No. 518,371.

To all whom it may concern:

Be it known that I, WILLIAM KOLB, a citizen of the United States, residing at the city of St. Louis and State of Missouri, have invented certain new and useful Improvements in Ironing Tables, of which the following is a specification.

My invention relates to certain new and novel improvements in ironing tables, and, 10 is a distinct and practical improvement to overcome certain important practical objections to, and defects in, ironing tables of a similar character.

The object of my invention is to provide 15 an ironing table that may be easily and readily set up and taken down and folded into a compact bundle.

A further object of the invention is to provide an ironing table that can be firmly 20 locked when set up so as to provide a very firm table.

A still further object of the invention is to provide an ironing table having a 25 pivotally mounted ironing board.

With the above and other objects in view, the invention consists in the new features of construction, arrangement and combination of parts hereinafter more fully described and finally pointed out in the claim hereto 30 appended.

Referring to the accompanying drawings forming a part of this specification wherein like characters of reference denote similar parts throughout the several views:

35 Fig. 1, is a perspective view of an ironing table constructed in accordance with my invention.

Fig. 2, is a longitudinal sectional view 40 of the ironing table in its set up position.

Fig. 3, is a side elevation of the ironing table in its knock-down position.

Fig. 4, is a bottom plan view of the ironing board.

In carrying out the aim of my invention, 45 I employ a table base consisting of a pair of end rails 1 which are connected by means of a pair of suitable spaced parallel arranged connecting bars 2.

An end standard, or table leg is hingedly 50 connected, as at 3, to each end rail 1. These standards, or legs each consist of a base cross-bar 4, the upwardly converging leg members 5 and the upper cross-bar 6. The 55 hinges 3 are attached to the upper faces of the end-bars and base cross-bars 4, as clearly shown in Fig. 1. The base cross-bars 4 are

positioned to the outer face of the end bars 1 of the table-base so that when the end standards are in their upright positions, the inner face of the bars 4 will engage the 60 outer face of the end rails 1 to prevent outward movement of the standards.

The means to prevent inward movement of the end standards in an arcuate path, 65 consists of locking means which comprises the brace members 7 which are pivotally connected at their lower ends, as at 8, to and between the connecting bars 2. The lower face of each brace member 7 is provided near its free, or upper end with a suitable recess 9 adapted to receive the cross-piece 10 connecting the legs 5 when the standards are in their upright position, and the brace-members are in their bracing position.

The upper face of each brace member 7 is provided near the free, or upper end thereof with a depression, or concaved seat 11 adapted to receive the lower end of a locking cam 12 which is fixed to a cross-rod 13, and, which in turn, is pivotally supported by the legs 5, above the cross-piece 10. The rod 13 being revoluble, permits the cam member 12 to be easily moved into, or 70 out of locking engagement with the recess 11 of the brace members 7, as is manifest.

When the cams 12 are in their locked position, which is in engagement with the recesses 11 of their respective brace member, 75 it will be observed that the end standards, or table-legs are held in a very firm position, as they cannot move outward past center on account of the cross-bars 4 engaging the base rails 1, and the brace members 8 being braced and locked against the cross-pieces 10.

90 14 indicates a suitable ironing board having an opening 15 near one end to receive the upwardly directed pin 16 which is supported by means of the cross bar 6 of one of the end standards. This arrangement 100 permits the ironing board to be turned upon a pivot when placing shirts or circular garments upon the board, as is manifest.

95 The board 14 is provided upon its under-face at the end opposite the opening 15, 105 with a pair of guide cleats 17 which are suitably spaced apart to receive the upper cross-piece 6 of the end standard at that end of the board. The inner or opposed faces 18 of the cleats 17 are suitably curved, 110 so that the board 14 may be swung or turned upon the pivot 16 without having to lift the

board from its supporting legs, or standards, as is manifest.

When the ironing table is in position for use, it appears as shown in Figs. 1 and 2, and when in its knock-down position, it appears as shown in Fig. 3 with the pivot pin 16 preferably lying in a recess 20 in the opposite cross-piece 6.

From the foregoing description, it is evident that I have generally improved this type of table, so as to increase its utility, durability and efficiency.

The many advantages of the herein described invention will readily suggest themselves to those skilled in the art to which it appertains.

I do not wish to be understood as having limited myself to the details of construction shown and described, but desire to have it understood that the invention I have shown in the drawings is merely illustrative, as it is manifest that various minor changes may be made in the exact construction and particular arrangement of parts without departing from the spirit of my invention, hence I reserve the right to make any such changes, or modifications as may fairly fall

within the scope of the appended claim when fairly construed.

What I claim is:

In a folding ironing table structure, a pair of end frames having upwardly converging side members constituting supporting legs, a base, hinges connecting the end frames with the base, a stationary round connecting the side members of each end frame, a round revolvably supported at its ends by the side members of each end frame, a cam member fixed to each revolvably supported round, a pair of brace members pivotally connected at their inner ends to the base, a recess formed in the lower face of each brace member at their outer ends adapted for contact with the stationary rounds when in operative position, a recess formed in the upper face of each brace member adapted for contact with the cam members of revolvble rounds for locking the end frames in operative position and a board supported by said end frames.

In testimony whereof, I have hereunto signed my name to the specification.

WILLIAM KOLB.
